UNITED STATES PATENT OFFICE

RICHARD DEUS, OF COLOGNE-DEUTZ, GERMANY

TOBACCO PIPE

Application filed January 29, 1930, Serial No. 424,334, and in Germany February 5, 1929.

My invention relates to tobacco-pipes. The main object of my invention is a pipe in which a rational combustion takes place so that residues are avoided. Another object 5 of my invention is a pipe which is easily to be cleaned. An embodiment of my invention is illustrated in the accompanying drawing in which

Fig. 1 is a longitudinal section of the pipe 10 according to the invention,

Fig. 2 a cross section of the pipe-bowl,

Fig. 3 a cross section of the pipe-tube,

Fig. 4 a longitudinal section of a cleaner 15 adapted to be inserted into the pipe-bowl, and

Fig. 5 a plan view of said cleaner.

The inner cylindrical surface of the pipe-bowl is provided with a lining *b* of asbestos. Adjacent said lining is a cylindrical grate 20 consisting of a number of superimposed rings *c* which are equally spaced from each other to form annular recesses between them. The said rings are held together by two or more longitudinal ribs *d*. In this way annular air spaces are formed through which a good circulation of the air around the tobacco and correspondingly a rational combustion without condensation is attained. In the lower part of the pipe-bowl a plane grate 25 *e* is provided which has a central opening *f* through which the smoke enters into the lower tapering part *g* of the bowl. Thence the smoke is sucked off to the mouth piece through a wound channel *i*¹ provided in a piece *i* which is inserted into the pipe tube *h*. In the bowl a rotatable cleaner is arranged which is guided in the annular grooves *c*¹ between the rings *c*. The cleaner has a shank *m* on which teeth *m*¹ are provided which fit into the grooves *c*¹. The shank is in connection with an arm *m*³ extending obliquely above the grate *e*. The said arm is also provided with teeth *m*² fitting into annular grooves of the plane grate *e*. The arm *m*³ ends in a hollow pivot *n* which has its bearing in the opening *f*. In this way the cleaner is adapted to be rotated. On the upper end of the shank *m* of the cleaner a ring *q* is fastened which has an inner conical

The said sections enclose the annular edge of the bowl at the free end thereof, and the said ring *q* also serves as a handle for the rotation of the cleaner. The cavity of the hollow pivot *n* is protected by a hood *r* which prevents fresh tobacco to fall through said cavity into the smoke channel *f*. The smoke is sucked off through the channel *i*² of the insertion *i* which may consist of paper or any other suitable material and which is enclosed in a shell *s* of porous material. In the pipe tube *h* openings *l* are provided through which fresh cooling air enters to flow around the shell *s*. From the wound channel *i*¹ of the insertion *i* the smoke 35 is sucked through a transversal bore *i*² and a central duct *i*³ into the mouth piece *h*.

I claim:

1. In a pipe, a bowl, a grate in said bowl, said grate comprising ribs spaced from each other to form annular recesses between them, and a rotatable cleaner in said bowl, said cleaner having cleaning teeth which fit into the said annular recesses.

2. In a pipe, a bowl, a grate in said bowl, such grate having a cylindrical portion which comprises superimposed rings spaced from each other to form annular recesses between them and a plane portion which consists of annular ribs and annular recesses 80 between them, and a rotatable cleaner in said bowl, said cleaner having cleaning teeth fitting into the recesses of the cylindrical portion and cleaning teeth fitting into the plane portion of the grate.

3. In a pipe, a bowl, a grate in said bowl, such grate having a plane portion, a cleaner rotatably mounted in said plane portion said cleaner having teeth adapted to clean said grate.

In testimony whereof I affix my signature.

RICHARD DEUS.
